UNITED STATES PATENT OFFICE.

FRANCIS DAVIDSON, OF CRYSTAL CITY, MISSOURI.

STEP-BEARING FOR VERTICAL SHAFTS.

SPECIFICATION forming part of Letters Patent No. 240,100, dated April 12, 1881.

Application filed January 22, 1881. (No model.)

To all whom it may concern:

Be it known that I, FRANCIS DAVIDSON, of Crystal City, in the county of Jefferson and State of Missouri, have invented a certain new and useful Improvement in Step-Bearings for Vertical Shafts, of which the following is a full, clear, and exact description, reference being had to the accompanying drawings, forming part of this specification.

10 My improvement consists in the hereinafter-described removable bearing intended especially for heavy vertical shafts for various purposes.

In the drawings, Figure 1 is a side view of the improvement. Fig. 2 is a section at $x x$, Fig. 4. Fig. 3 is a horizontal section at $x' x'$, Fig. 2, with plan of parts below the section-line. Fig. 4 is a horizontal section at $x^2 x^2$, Fig. 2, with plan of parts below the section. 20 Fig. 5 is an enlarged detail section of the lower end of the shaft at $x x$, Fig. 4, showing the bearing-block in position in the central socket of the shaft; and Fig. 6 is a similar section, showing this block loosened in the socket.

25 A is the step casting, made with a socket to receive the lower end of the vertical shaft B, and an oil-chamber, C, closed by a plate, D, held in place by bolts d. The joint between the plate D and the casting is made oil-tight, so that the chamber C may be kept full of oil.

d' is a plug fitting in a hole in the plate D, through which hole the oil may be drawn from the chamber C.

35 The lower end of the shaft B has an axial socket, b, which may be cylindrical for most of its length, and whose lower part, b', is flaring or conical, and in this part b' fits tightly the frusto-conical top e of the bearing-block E. The lower part, e', of the bearing-block may be cylindrical in form, and may be of 40 larger diameter than the conical part e. The bottom of the bearing-block E turns upon the fixed step-block F, which is made angular at its lower part, f', and fits snugly in a recess of the step-casting to hold it in place. The upper part, f, of the step-block may be cylindrical, as shown, and of diameter similar to the part e' of the step-block, more or less.

45 50 The plate or gate D has projections D' bear-

ing against the outer side of the step-block F, to prevent its outward movement.

The top of the step-block F has an oil channel or groove, e², to conduct the oil inwardly to the bearing-surfaces between the blocks E and F.

The shaft-socket b in the step-casting A has a number of recesses to receive side bearing-block, G, whose inner sides are made to fit the shaft. The top of the step-casting extends outward in a flange, a, to give bearing for jacks to lift the shaft when removing the bearing-blocks. The upper ends of the jacks have bearing beneath a flange, b³, surrounding the shaft B.

65 The cylindrical (upper) portion of the socket b contains a drift-block, H, made to fit freely in the socket, the purpose of which is to force the bearing-block E downward and loosen it in the socket to allow it to drop to the bottom 70 of the chamber C, when the step-block F has been removed through the mouth a', when the gate D has been taken away. The drift-block H is forced down for the said purpose by a wedge, I, which extends through a diametric 75 mortise, b², in the shaft, and which rests in a key-seat, h, of the block. To limit the descent of the drift-block H the block has a diametric hole, h', through which is passed a bar, J, extending through the mortise b². Thus the bar J 80 sustains the drift-block H in the absence of the block E and when in its lower position, as seen in Fig. 6.

f² is a hole for the insertion of the claw of a pull-rod, by which the block F is drawn out 85 of the chamber C.

I prefer to form the lower end of the drift-block H with a diametric rib, h², which enters a groove in the top of the bearing-block E, so as to hold them in their relative positions. 90 By means of this connection and a key, I, the block E might be prevented from turning in the conical socket b' when not fitted in tightly.

95 It will be observed that by simply removing the pressure of the shaft from the step-block F it can be taken out, and that the bearing-block E can then be forced out of its socket and drawn out of the oil-chamber. These blocks can then be readily lined up and returned and the jacks removed from between the flanges a 100

and b^3 , allowing the shaft to descend upon the blocks.

I claim as my invention—

1. The drift-block H and key I, in combination with the bearing-block E and shaft B, formed with socket b and mortise b^2 , the said block being located in the said socket b, and the said key extending through the said mortise, as set forth.

2. The combination, with a vertical shaft, 10 of the removable step-bearing blocks and the step-casting containing oil-chamber C, closed by removable gate D, substantially as set forth.

FRANCIS DAVIDSON.
